(57) **CLAIM**

The ornamental design for a nesting bucket, as shown and described.

DESCRIPTION

FIG. 1 is a perspective view of the nesting bucket of the subject invention;

FIG. 2 is a front plan view of the nesting bucket of the subject invention;

FIG. 3 is a rear plan view of the nesting bucket of FIG. 1;

FIG. 4 is a left plan view of the nesting bucket of FIG. 1;

FIG. 5 is a right plan view of the nesting bucket of FIG. 1;

FIG. 6 is a top plan view of the nesting bucket of FIG. 1; and,

FIG. 7 is a bottom plan view of the nesting bucket of FIG. 1. The broken line showing of the figures is for the purpose of illustrating environment and forms no part of the claimed design.
